UNITED STATES PATENT OFFICE.

MORRIS GARDNER TALCOTT, OF TALCOTTVILLE, CONNECTICUT.

OIL BURNER.

Application filed November 24, 1919. Serial No. 340,216.

To all whom it may concern:

Be it known that I, MORRIS GARDNER TALCOTT, a citizen of the United States, residing in Talcottville, in the county of Tolland and State of Connecticut, have invented a new and Improved Oil Burner, of which the following is a specification.

My invention relates more especially to the class of oil burners employing fluid, as air, under pressure, as an agent for atomizing or mixing, and an object of my invention, among others, is to increase the efficiency of such oil burners.

One form of burner embodying my invention and in the construction and use of which the objects herein set out, as well as others, may be attained, is illustrated in the accompanying drawings, in which—

Figure 1 is a view in lengthwise section through the outer end of an oil burner, including the burner tip, embodying my invention.

Figure 2 is an end view of the same.

Figure 3 is a detail view, scale enlarged, in cross section through the burner tip looking toward the end.

My invention relates to the well known class of oil burners consisting of a nozzle including an outer tube for supplying air and an inner tube for supplying fuel, as oil, the air and oil being mixed to a greater or less extent before they emerge at the end of the nozzle. As the general structure of these nozzles or burners is well understood by those skilled in the art only the outer end thereof has been shown by me in the drawings herein for the purpose of illustrating my invention.

In the accompanying drawings the number 5 indicates the outer tube of a burner that may be of any desired shape, preferably round, and that will be connected at its inner end with any means for supplying fluid, as air, to the mixing chamber 6 within the burner. A fuel supply pipe 7 extends from any suitable supply of fuel, as oil, within the chamber 6 to or near the outer end thereof, it being understood that the fuel will be supplied under such pressure as may be desired, the tubes being of such relative size and the pressures being regulated to supply the proper amounts of fuel and air for the special purposes for which the burner may be employed, my improved burner being especially adapted for use with air un-

der low pressure and with an oil pressure as may be desired.

A novel feature of my improved device consists in the means for spreading the oil and causing it to be thoroughly mixed with the air, such device embodying a spreader having a receiving recess located in the path of movement of the oil as it is forced out of the pipe 7, this recess thus causing the oil to be thrown backwardly and outwardly in a spray. This spreader and receiving recess may be arranged in various ways to accomplish the desired results, in the structure herein shown a tip 8 having an oil passage 9 extending therethrough being secured to the end of the pipe 7. The inner end 10 of the tip is recessed to form an annular chamber between it and the inner surface of the pipe, and in the structure herein shown a flange 11 on the tip rests against the end of the pipe, the tip being preferably secured to the pipe as by means of intermeshing screw threads.

A cap 12 is screwed onto a nipple 13 projecting from the tip, said cap comprising a spreader 14 supported by posts 15 extending from its base and disposed to provide outlet openings 16.

A receiving recess 17 is formed on the inner surface of the spreader and opposite the mouth of the passage 9, this recess being preferably of conical shape and located directly opposite the passage 9, so that as the oil or other fuel under pressure is forcibly ejected from said passage, such fuel will enter the receiving recess, the sloping walls of which will cause the fuel to be thrown backwardly in a diagonal direction through the outlet openings 16 into the current of outgoing air. This causes the fuel to be divided into a very fine spray and to be thoroughly commingled with the air, thus producing a mixture in prime condition for ignition at the mouth of the burner, which burner will be projected into the combustion chamber, as of a furnace or other structure.

The posts 15 are preferably tapered from their inner edges outwardly, thus offering little obstruction to the passage of fuel as it passes out from the receiving recess in the spreader.

In accordance with the provisions of the patent statutes, I have described the principles of operation of my invention, together with the device which I now consider to represent the best embodiment thereof; but I

desire to have it understood that the device shown is only illustrative, and that the invention may be carried out by other means.

I claim—

5. 1. A burner comprising a fuel supply pipe, an air tube surrounding said supply pipe and having an unobstructed open mouth concentric with said supply pipe, and a spreader having an unobstructed receiving recess in 10 its under surface to receive the oil separately from the air, and force such oil, as it passes from said pipe, backwardly into the air currents in the open mouth of said air tube.
- 15 2. A burner comprising a fuel supply pipe, an air tube surrounding said supply pipe and having an unobstructed open mouth concentric with said supply pipe and a cap secured to said pipe and having a spreader located opposite the mouth of said pipe with a clear 20 and unobstructed space between the entire end of said pipe and said spreader and mouth, said spreader comprising an imperforate surface with a receiving recess in its inner face located opposite the outlet from

said pipe to receive fuel separately from the 25 air as such fuel is delivered therefrom and to throw it backwardly in a spray into the air currents in the open mouth of said air tube.

3. A burner comprising a tip including a 30 body having a fuel passage therethrough, and a cap secured to said body and comprising a spreader located opposite the mouth of said fuel passage and having an imperforate surface including a recess in said surface opposite said fuel passage to deliver fuel in substantially all directions backward and laterally outwardly from the sides of 35 said cap.

4. A burner comprising an air tube, a fuel 40 supply pipe located within said tube, and a cap secured to said pipe and comprising posts with a spreader secured to the outer ends of the posts and an unobstructed receiving recess located in the under surface 45 of said cap opposite the opening from said supply pipe.

MORRIS GARDNER TALCOTT.
